UNITED STATES PATENT OFFICE

FRED A. ISAACSON, OF CHICAGO, ILLINOIS

FREIGHT CAR CONSTRUCTION

Application filed May 12, 1930. Serial No. 451,618.

This invention relates to freight cars of the kind provided with metal roofs that are supported at the eaves of the car on side fascia members that are secured to the vertical outer faces of the car side plates. Heretofore it has been customary to make such sheet supporting members of wood and to bolt them to the side plates. When such eaves fascia boards are made of well seasoned lumber and are properly applied and kept in proper condition, they are very serviceable and satisfactory; but otherwise they are liable to shrink, warp, split or rot out and wear around the bolt holes and thereby cause the metal roof to sag at the eaves and thus permit the joints thereof to leak.

The principal object of the present invention is to overcome the disadvantages above stated; that is, to dispense with the eaves fascia boards and the securing bolts therefor. Other objects are reduced cost of manufacture and maintenance, compactness of design, and increased strength at the eaves. The invention consists principally in dispensing with the eaves fascia boards and in adapting metal members to perform the functions thereof together with other functions. The invention also consists in the parts and in the combinations and arrangements of parts hereinafter described and claimed.

In the accompanying drawings, which form part of the specification and wherein like symbols refer to like parts wherever they occur,

Fig. 1 is a plan view of a freight car embodying my invention;

Fig. 2 is an enlarged vertical cross-section through the eaves portion of the car on the line 2—2 in Fig. 1;

Fig. 3 is a vertical cross-section through the roof at one of the seams; and

Fig. 4 is a perspective view of a portion of the metal side fascia.

Referring to the accompanying drawings, my invention is shown in connection with a freight car comprising Z-bar side plates 1 that are preferably arranged with their webs horizontal and with one flange 2 in and extending upwardly. The Z-bar side plates on opposite sides of the car are connected by met-

al carlines 3, preferably of substantially inverted channel-shape provided with outstanding base flanges 4 at the lower edges of their side walls. As shown in the drawings, each end of a carline 3 is rigidly secured to an adjacent side plate 1 by means of an angle-shaped bracket 5, the two flanges of which are riveted one to the undersides of the base flanges 4 of said carline and the other to the inner face of the upstanding inner flange 2 of said side plate.

The car is provided with a metal roof, preferably of the flexible single-course type, which comprises metal roof sheets 6 that slope downwardly from ridge to eaves of the car between carlines and are supported between the side plates on purlines 7 secured to the undersides of said carlines. The roof sheets 6 are narrower than the spaces between the channel portions of the carlines and are provided with depending eaves flanges 8 that overhang and are spaced outwardly from the upstanding inner flanges 2 of the side plates. The roof sheets are provided along their adjacent side margins with upstanding seam flanges 9 that are loosely connected by weatherproofing seam covers 10 of substantially inverted channel-shaped section that have outstanding base flanges 11 that bear against the body portions of the sheets inside the upstanding side seam flanges thereof. The seam covers 10 rest on and are riveted to the flat tops of the carlines 3 and are provided at their eaves ends with depending flanges 12 that overhang and are spaced outwardly from the depending eaves flanges 8 of adjacent sheets.

At the eaves of the car the roof sheets are movably supported on metal side fascia members A that extend longitudinally of the side plates 1 and are riveted or otherwise permanently secured to the outer side faces of the upstanding inner flanges 2 of said side plates. Each side fascia member A comprises a rolled metal member of substantially T-shaped cross-section; that is, it comprises a vertically disposed stem portion 13, which is provided at its top with a sheet supporting flange 14 that extends on opposite sides of said stem portion at an oblique angle thereto, the angle corresponding to the slope of the roof sheets.

As shown in the drawings, the top flange 14 projects a greater distance on one side of the stem 13 of the T-shaped metal side 5 fascia member A is rigidly secured flatwise by means of rivets 15 to the outer face of the upstanding inner flange 2 of the side plate 1, with the long inner side of the top flange 14 of said fascia member spaced above and 10 extending inwardly and upwardly over the upper edge of said upstanding side plate flange. The short outer side of the flange 14 slopes downwardly and outwardly beyond the stem 13 and serves as a drip edge and as 15 a means for deflecting any water that might be blown beneath the depending eaves flanges 8 of the roof sheets 6. The metal fascia members A are rolled in convenient lengths and are arranged end to end on the car with their 20 adjacent ends welded together to form smooth sheet supporting surfaces that extend continuously from end to end of the car.

By the arrangement described, the metal fascia members become part of the car frame 25 and thus serve to strengthen and stiffen the side plates, particularly at the doorways; they also provide rigid sheet supports which prevent sagging and leakage of the roof at the eaves; and they also overcome all of the 30 disadvantages associated with the use of fascia boards heretofore used for supporting the eaves portions of the car roof. Another advantage of the foregoing arrangement is that it decreases the overall width of the roof 35 without decreasing the width of the supporting surfaces of the fascia members, thereby permitting the cars to be built higher at the eaves and still come within the limiting outline for freight cars.

40 It is evident that the metal fascia members hereinbefore described are applicable to cars having side plates and roofs of various constructions. Therefore, I do not wish to be limited to the details of construction shown 45 and described.

What I claim is:

1. A freight car comprising side plates having upstanding flanges extending longitudinally thereof, a metal roof for said car, 50 and metal side fascia members for supporting the eaves ends of said roof, each of said side fascia members comprising a stem portion that is permanently secured flatwise to the outer face of the upstanding flange of an 55 adjacent side plate and a top roof supporting flange spaced above and extending inwardly over the upper edge of said upstanding side plate flange.

60 2. A freight car comprising side plates having upstanding flanges extending longitudinally thereof, a metal roof for said car, and metal side fascia members for supporting the eaves ends of said roof, each of said side fascia members comprising a stem portion 65 that is permanently secured flatwise to

the outer face of the upstanding flange of an adjacent side plate and a top roof supporting flange spaced above and extending inwardly over the inner edge of said upstanding side plate flange, said roof supporting flange also extending outwardly beyond the outer face of said stem portion. 70

3. A car roof comprising Z-shaped side plates arranged with one flange extending upwardly along the inner edges thereof, and a roof supporting flange at the top of the upwardly extending flange of each side plate, said roof supporting flange extending on opposite sides of said upwardly extending flange at an inclination approximately 80 equal to the pitch of the car roof, the inner portion of said roof supporting flange overhanging the upwardly extending flange of said side plate. 85

Signed at Chicago, Illinois, this 3rd day of May, 1930.
